(57) **CLAIM**

The ornamental design for a kettle body, as shown and described.

DESCRIPTION

FIG. 1 is a top, front, right side, perspective view of a kettle body;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a top, front, right side, perspective view thereof, shown in a condition of use.

In the drawings, the broken lines are for portions and environmental structure that form no part of the claimed design.
